2,616,500

TICKET ISSUING MACHINE

Reuben H. Helsel, Long Island City, N. Y., assignor to General Register Corporation, Long Island City, N. Y., a corporation of New York

Application May 24, 1949, Serial No. 95,054

6 Claims. (Cl. 164—48)

1

This invention relates to a ticket issuing machine and while of more general application is particularly adapted to machines of the hand-powered type.

Particularly in the case of ticket issuing machines which are to be operated by the public rather than skilled operators, it is necessary that the machine should be of a type susceptible to "fool-proof" operation. Such machines, for example, are those which are adapted to be released for operation by insertion of a coin and then manually manipulated by actuation of a lever or the like to issue a ticket or transfer when installed on a bus, street car or other vehicle or in some such locality as a subway or elevated station. The invention will be particularly described in connection with a machine of this type.

The broad object of the present invention is to provide a machine of this general character which is simple in construction and operation and essentially incapable of being jammed by improper manipulation.

A further object of the invention is the provision in a ticket issuing machine of an improved ticket strip feeding mechanism.

Another object of the invention is the provision of an improved strip severing mechanism which will insure proper severance of tickets from the supply strip.

These and other objects of the invention, particularly relating to details of construction and operation, will become apparent from the following description read in conjunction with the accompanying drawings in which:

Figure 1 is a side elevation of a coin-operated manually powered ticket issuing machine embodying the invention with the cover opened to reveal internal details of construction;

Figure 2 is a similar view in the form of a section taken on a vertical plane behind the coin detecting and controlling mechanism;

Figure 3 is a vertical section similar to Figure 2 but taken on a plane still further toward the rear and showing in particular parts behind the ticket guiding and feeding elements;

Figure 4 is a further section taken on a vertical plane still further to the rear to show various details more clearly;

Figure 5 is a front elevation of the machine;

Figure 6 is an enlarged fragmentary vertical section showing in particular the feeding means and severing knife;

Figure 7 is a section similar to Figure 6 but showing certain elements behind those of Figure 6;

Figures 8 and 9 are fragmentary vertical sections particularly showing portions of the coin control mechanism; and

Figure 10 is a diagram illustrating the application of the invention to a motor operated ticket machine.

2

The machine as illustrated comprises a housing 2 in which are mounted various supporting frame elements which will be evident and need not be particularly described. These elements serve as mountings for the various movable parts of the machine. The housing is provided with a hinged door 4 provided with a lock 6 under the control of someone authorized to have access to the interior of the machine to replace ticket stock and to remove accumulated coins. The housing is provided with clamping means 8 engageable with a post indicated at 10 forming part of the structure of a vehicle or other carrying device.

The housing is provided with a slot 12 for the insertion of an operating coin indicated at C in Figure 1. Exposed to view in the front of the machine is the handle 14 of an operating lever 16, a front surface 18 of which may have provided thereon an instruction to "Press Down." A ticket chute 20 is arranged to deliver the issued ticket into a receptacle indicated at 22 from which the patron may pick up a ticket.

Referring to Figure 1 it will be noted that the coin slot 12 communicates with a coin chute 24 which delivers a coin to a coin testing device 26 and thence to a machine releasing device 28. These devices are conventional and of types well known in the art of coin operated devices and need not be described in detail since in themselves they form no part of the invention. In brief, they serve to discard coins of wrong denominations, counterfeits, and slugs and serve to route to the releasing mechanism only proper coins of the correct denomination.

Referring to Figures 8 and 9 there are disclosed therein the releasing elements. A shaft 30 carries a member 32 which is provided with a pocket for the reception of a coin C so that when the coin is present in the pocket it will cam outwardly a pin 34 of a spring-controlled detent member 36 which, in the absence of a coin, will prevent more than a limited rotation of the shaft 30. A full-stroke mechanism is provided by a detent 38 cooperating with teeth 40 carried by the member 32 which has relieved portions 42 and 44. This also is conventional and insures that once the shaft 30 has been rotated through a small arc clockwise as viewed in Figures 8 and 9, the shaft cannot return to a counterclockwise position until it is given a full-stroke which brings the relieved portion 42 opposite the detent 38. Thereafter, if the shaft 30 has a predetermined degree of counterclockwise movement, it cannot be again moved clockwise until it has been returned substantially to its extreme counterclockwise position. These elements are also conventional. The operation of the novel portion of the present mechanism depends upon the imparting to the shaft 30 of a full clockwise movement followed by a full counterclockwise restoring movement to its

original position. Figure 8 illustrates the original position and Figure 9 illustrates a later position of the parts attained after a predetermined initial clockwise movement of the shaft 30.

Referring now particularly to Figure 4, the lever 16 is pivoted at 46 and urged upwardly by a strong spring 48 against a stop pin 50. Pivoted to the lever 16 at 52 is a link 54 provided with ratchet teeth 56 held in mesh with a pinion 58 by a backing roller 60. The pinion 58 has its hub secured to the shaft 30 so that oscillating movements are imparted to the shaft by movement of the lever 16.

A bell 62 is provided which will sound to indicate proper operation of the machine. A hammer 64 is carried by a lever 66 pivoted at 68 which lever is provided with a flat portion 70 arranged to be engaged flatwise by a corresponding portion of a lever 72 pivoted at 74 and urged clockwise by a spring 76 anchored at a fixed pin 66. This arrangement is such that normally the hammer 64 is held slightly spaced from the bell to prevent muffing of the sound of the bell after it is struck. It will be noted that the terminus 78 of the flat 70 is slightly to the left of the center of the pivot 68.

A link 80 is pivoted to the lever 66 at 82 and is urged upwardly and counterclockwise about its pivot by a spring 84 which is effectively weaker than the spring 76 and tends to hold the link 80 in contact with the pin 86. The upper end 88 of the link 80 is flat and is located below a pin 90 carried by the lever 16. As will be evident from the relationship of the parts in Figure 4, as the lever 16 is depressed the pin 90 will drive the link 80 downwardly and will rock the lever 66 clockwise, the point 78 forcing the lever 72 counterclockwise against the action of spring 76. As the pin 90 moves downwardly it will rock toward the left and eventually clear the link 80 whereupon the strong spring 76 through the lever 72 will rock the lever 66 sharply counterclockwise with the result that by virtue of overrun its hammer 64 will strike the bell, being immediately released by the restoration of the levers 72 and 66 to the position illustrated in Figure 4. Upon return of the lever 16 the pin 90 will again move above the link 80 which will rock toward its initial counterclockwise position restoring the parts for a further bell-striking operation.

Referring now to Figure 3 a cam 92 is carried by a hub 93 secured to the hub of the pinion 58 and accordingly to the shaft 30. The cam 92 operates between a roller 94 and a pin 96 carried by a link 98 which is pivoted at 100 to a disc 102 pivoted on a fixed pin 114. A spring 104 is anchored to the frame and acts on an arm extending laterally from the link 98 serving, as will be evident from Figure 3, to urge the link 98 both downwardly and counterclockwise so that its lower end will normally occupy the position illustrated in Figure 3 with respect to the cam 92. The disc 102 is provided with slot 106 into which extends a pin 108 carried by an arm 110 secured to a hub 112 journalled on the pin 114. A second arm 112 (Figure 6) also carried by the hub 114 forms with the arm 110 a yoke carrying a knife 116 provided with a cam-like extension 118 serving to engage and suitably deflect a yielding spring-like fixed blade 120 which is secured to the frame at 122. As will appear the movable knife 116 has an arcuate movement which causes its sharpened edge to be brought into severing relationship with the cooperating sharpened edge

of the yielding blade 120, the extension 118 serving to produce slight movement of the yielding blade 120 so as to insure the proper cutting relationship between the blade edges.

5 A pawl 124 is pivoted on the pin 108 and is urged in a clockwise direction as viewed in Figure 7 by a spring 126 which reacts between the pawl and the lever 110. On fixed pins 128 and 130 there are pivoted a pair of detents 132 and 134 which are urged respectively counterclockwise and clockwise by a spring 136 connected to these detents. The detent 132 is provided with an ear 138 extending forwardly as viewed in Figure 7 with which cooperates a pin 140 extending rearwardly from the tail portion of the pawl 124.

A disc 142 is carried by a hub 144 which is journalled on the hub 112. This disc is provided with a series of separate projections 146 and, as indicated in Figure 7, the pawl 124 rests on the periphery of the disc 142 slightly to the rear of one of the projections 146 while the detents 132 and 134 embrace between them another of the projections 146 to prevent movement of the disc in either direction.

20 A pinwheel 148 is carried by the hub 144 and has a series of ticket strip feeding pins corresponding in number and indexing to the projections 146. A slotted ticket strip guide blade 150 extends about the periphery of the pinwheel, the slot providing clearance for the passage of the pins of the pinwheel 148. A cover member 152 contoured to correspond to the guide 150 is pivoted at 153 and serves to hold the ticket strip 25 against the guide 150 so as to insure that the openings in the ticket strip are properly engaged by a plurality of pins of the pinwheel, this cover member being slotted to provide clearance for rotation of the pins. It is provided with an ear 156 with which there engages the spring 158 normally holding it in downward position.

To prevent operation when the ticket strip approaches exhaustion a finger 160 is provided which is pivoted at 162 so as to be held in a clockwise position, compared with that illustrated in Figure 6, when there is a ticket strip threaded in the machine over the pinwheel. An ear 164 of this finger engages a crank arm 166 (Figure 1) of a shaft 168 journalled in supports in the frame so that whenever ticket strip supply is present and in position to be fed a lateral extension 170 of the shaft 168 is held clear of the coin slot 12, a spring 172 tending to hold this lateral extension in position across the coin slot whenever the finger 160 occupies the position illustrated in Figure 5 so as to prevent the insertion of a coin. Additionally there is provided a lever the end of which at 171 is adapted to be manually positioned across the coin slot 12 by movement of its end 173 whenever it is desired that the machine should not be operated by insertion of a coin, this lever being located within the housing so that it can be positioned to prevent entrance of a coin, this positioning being done by someone authorized to gain access to the interior of the machine. When the machine is to be operated this lever is withdrawn so as not to prevent coin insertion.

70 A counter 174 is provided to register the issue of tickets, the arm 176 of this counter being connected to a link 178 which is in turn pivoted on a pin 180 carried by the arm 182 forming part of the knife supporting yoke.

When the machine is in rest position the various parts occupy the positions illustrated in all of the figures except Figure 9. If the ticket supply strip is in position to be fed by the pinwheel the

finger 160 is depressed by the ticket strip and accordingly the coin slot is open. The insertion of a proper coin will result in its passing into the position illustrated in Figure 8 so that the shaft 30 is capable of being moved when the lever 16 is rocked downwardly.

As the lever 16 is moved downwardly the cam 92 is rotated in a clockwise direction as viewed in Figure 3 and serves by acting on the roller 94 carried by the link 98 to raise this link against the action of spring 104 which spring also holds the link in contact with the fixed disc 99. The lifting of the link rotates the disc 102 and through its slot 106 the pin 108 so as to rotate the knife 116 and its carrying yoke in clockwise direction as viewed in Figure 7. The pin 108 carries the pawl 124 so that the pin 140 will engage the ear 138 of the detent 132. Since the pawl 124 is restrained from clockwise movement by reason of its resting on the disc 142 the pin 140 will effect clockwise rotation of the detent 132 to release the projection 146 which was engaged thereby just prior to the engagement of another projection 148 by the pawl 124. Accordingly, the disc 142 and the pinwheel 148 are released for strip feeding rotation and pawl 124 drives the pinwheel through a fifth of a rotation advancing the ticket strip through a length corresponding to one ticket, which length is defined by the spacing between the centers of adjacent holes in the strip. The strip is fed over the guide 150 and below the cover 152, being projected below the end of the fixed knife 120, the movable knife having been now moved sufficiently clockwise to clear an opening for the passage of the strip. As soon as a slight advance has been given to the disc 142 the detent 132 will be released and will rest first on the top of a projection 146 and then on the periphery of the disc in position to engage and arrest the next projection. At the completion of the full-stroke the next projection will clear the detent 134 and will be arranged between it and detent 132 so that a precise fifth of a revolution is imparted to the pinwheel.

At this end of the stroke the cam 92 will clear the roller 94 so that the link 98 will snap downwardly under the action of spring 104 with resulting reversal of rotation of the disc 102 and the movable knife which will snap suddenly upwardly to sever the projected portion of the ticket strip by cooperation with the fixed flexible blade 120. The severed ticket will drop through the chute 20 into the receptacle 22. In the reverse movement the pin 140 of the pawl 124 will engage the ear 138 to be cammed inwardly thereby and ultimately pass the rear of this ear so that the pawl 124 will be restored into the position illustrated in Figure 7 in advance of the next projection 146.

The ringing of the bell will, of course, occur during the downward stroke of the lever 16 as previously described. The oscillation of the knife will advance the counter 176 to register the issue of a ticket. During the downward movement of the lever 16 the coin which released the mechanism will drop into the coin receptacle 28.

The release of the lever 16 for upward movement will rotate the cam 92 in a counterclockwise direction and this will cam the roller 94 toward the left as viewed in Figure 3 against the action of spring 104 until the roller is cleared whereupon the link 98 will be rocked by the spring 104 to the position illustrated in Figure 3. If it should happen that due to the accumulation of dirt or other cause the link 98 was not fully restored by the spring 104 this will be additionally insured

by the action of the spring 48 through the action of the lower side of the cam 92 on the pin 96. All of the parts are accordingly restored to their initial positions.

5 A coin return, not shown, may be provided in the door 4 to return to a patron coins which are of an incorrect denomination to release the mechanism.

10 It will be evident from the foregoing that there is provided, in accordance with the invention, a simple and compact mechanism for a hand-powered machine which will insure proper issuance of a precise ticket length with completely effective locking of the ticket strip advancing means to prevent the possibility that any tickets may be pulled through the mechanism without the insertion of the proper number of coins. It will be noted that the pinwheel is released to the extent that it might be given more than a fifth 15 of a revolution only during a very restricted phase of the operation and also only at a time prior to the opening of any space between the knives, i. e., only following rocking of the detent 132 clear of the engaged projection 146 until slight 20 advance of disc 142 by the pawl 124 after which the detent is again released by pin 140. As a result, it is quite impossible for anyone to seize an issuing ticket and attempt to secure more than one during an operation.

25 30 It will be evident that the mechanism may be utilized in machines which are not coin-controlled, this end being merely achieved by leaving the shaft 30 free for motion at any time.

35 The mechanism may also be motor driven and 35 a simple mode of accomplishing this is illustrated in Figure 10.

40 A motor 184 drives reduction gearing, indicated at 186 and 188, the shaft 190 which carries a cam 192 corresponding to the cam 92 previously described which is arranged to act upon a roller 194 carried by a link 196, these respectively corresponding to the elements 94 and 98 previously referred to. A solenoid 200 is connected to the power line 202 through a manually operable key 45 switch 204 which may be located in any convenient position. An armature 206 normally retracted by a spring 208 serves as a latch for a member 210 pivoted at 212 and urged clockwise by a spring 214, its clockwise movement being 50 subject to limitation by a stop pin 216. The member 210 is provided with a projecting portion 218 arranged to act upon the upper member of a switch having contacts 220 which are in series with the motor 184 and the line. The member 55 210 carries at its upper end a pin 222 engageable by the cam 192.

55 60 As will be evident, the mechanism may be essentially similar to that previously described with the exception of the hand lever 16 and its operation connections which may be omitted.

The operation of the modification in accordance with Figure 10 is as follows:

65 Contact is provided at 204 momentarily to energize the solenoid 200. This will retract the detent 206 permitting the member 210 to rock clockwise to close the contacts at 220 and thus energize the motor. The motor will thereupon drive the cam 192 clockwise so that it acts upon the roller 194 moving it upwardly and thereafter releasing it in the same fashion as previously described in connection with the hand-operated machine. A ticket will accordingly be issued and cut off as previously detailed. In the case of this present machine, however, the cam 192 does not oscillate but rather rotates continuously in the clockwise 70 75

direction. As it approaches the rest position which is illustrated in Figure 10 it will engage the pin 222 rocking the member 210 counterclockwise so that the motor circuit is broken and the member is positioned to be engaged by the detent 206 which will have been released by the release of the button 204. The overrun of the cam 192 will cause it to pass the pin 222 so that the parts will be restored to their initial positions. It will, accordingly, be evident that a momentary depression of the button will cause the machine to pass through a single cycle for the issuance of a ticket. It will, of course, be evident that this machine may also be coin-controlled merely by preventing the solenoid circuit from being closed unless a proper coin is inserted.

What is claimed is:

1. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl carried by said element and engageable with teeth on said toothed member, and said severing means comprising a movable blade, carried by said element, and a relatively fixed blade.

2. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl carried by said element and engageable with teeth on said toothed member, and said severing means comprising a movable blade, carried by said element, and a relatively fixed, flexible blade.

3. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl carried by said element and engageable with teeth on said toothed member, and said severing means comprising a movable blade, carried by said element, and a relatively fixed blade, and said means for imparting oscillatory movements to said element comprising an actuating member, a spring urging said actuating member in one direction, and an element constructed and arranged to move said actuating member in opposition to said spring.

4. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl

carried by said element and engageable with teeth on said toothed member, and said severing means comprising a movable blade, carried by said element, and a relatively fixed blade, and said means for imparting oscillatory movements to said element comprising an actuating member, a spring urging said actuating member in one direction, and an element constructed and arranged to move said actuating member in opposition to said spring and to release said actuating member for rapid movement under the action of said spring, said rapid movement serving to effect movement of the movable blade to sever the ticket strip.

5. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl carried by said element and engageable with teeth on said toothed member, and said severing means comprising a movable blade, carried by said element, and a relatively fixed blade, and said means for imparting oscillatory movements to said element comprising an actuating member, a spring urging said actuating member in one direction, and a cam constructed and arranged to move said actuating member in opposition to said spring.

6. A ticket issuing machine comprising means for guiding a ticket strip, means for feeding a ticket strip along said guiding means, and means for severing tickets from said strip, said feeding means comprising a rotary pin wheel engageable in openings in said ticket strip, a toothed member moving with said pin wheel, an oscillatory element mounted concentrically with said pin wheel and toothed member, means for imparting oscillatory movements to said element, and a pawl carried by said element and engageable with teeth on said toothed member, and said severing means comprising a movable blade, carried by said element, and a relatively fixed blade, said fixed and movable blades overlapping when said machine is in rest position to close the path of advance of the ticket strip.
